UNITED STATES PATENT OFFICE.

ALFRED M. ROWE, OF CHICAGO, ILLINOIS.

FEED-WATER HEATER.

SPECIFICATION forming part of Letters Patent No. 359,634, dated March 22, 1887.

Application filed November 9, 1886. Serial No. 218,441. (No model.)

To all whom it may concern:

Be it known that I, ALFRED M. ROWE, a citizen of the United States, residing at Chicago, in the county of Cook and State of Illinois, have invented certain new and useful Improvements in Feed-Water Heaters, of which the following is a specification.

It has heretofore been proposed in feed-water heaters to provide a large area of heating-surface by passing steam through a set of pipes submerged within a water-chamber. Under such arrangement, however, the shell or casing of the water-chamber is exposed to the air, which tends to cool the same, and hence to cool the feed-water in contact with the inner side or wall of said shell or casing, thereby opposing to an objectionable extent the action of the heating agent that is employed for raising the temperature of the water to a desirably high degree before it passes to the boiler. It has also been proposed to remedy such defect by conducting the water through pipes or passages submerged or exposed within one or more steam-chambers.

Certain objects of my improvement, generally stated, are to provide means for the circulation of the water from and to one end of the steam-chamber; to distribute the exhaust-steam equally around the water-pipes; to promote the circulation of steam around the water-pipes; to avoid back-pressure of the exhaust-steam; to provide means whereby the apparatus shall have an increased capacity for permitting the collection of sediment from the feed-water without obstructing the inlet and without necessitating the objectionable feature of frequently blowing off the sediment; to provide for the expansion and contraction of the water-pipes, and to provide certain novel and improved features of construction all tending to the general efficiency of the apparatus.

To these and other useful ends my invention consists in matters hereinafter described, and particularly pointed out in the claims.

As a prominent feature of my improvement, I provide two concentrically-disposed steam-chambers, whereof the inner steam-chamber communicates with the surrounding outer steam-chamber solely at one end, and is provided at its opposite end with the inlet through which steam is let into the apparatus. In con-

nexion with said two chambers I provide water-passages having their walls exposed within both chambers, the outer one of which latter is provided with a steam-outlet, whereby steam is admitted into the one chamber will be compelled to first traverse the heating-surface thereto and to then pass through and traverse the heating-surface exposed in the other chamber. By such means an effective circulation of steam over the entire area of heating-surface is maintained and highly economical results attained.

A further feature of my improvement is that I incorporate within the wall intervening between the inner and outer steam-chambers a series of water-pipes arranged to expose their surfaces in part within one and in part within the other of said chambers, which arrangement presents a greater area of heating-surface than if an annular water-chamber were employed between the two steam-chambers.

A further feature consists in a large water-supply pipe or cylindric water-chamber arranged centrally within a steam-chamber and supplying a lower settling-chamber, from which latter a set of return water-pipes rise and stand around the centrally-disposed water-supply chamber, whereby a large area of heating-surface is exposed within the steam-chamber, the water conducted through comparatively small passages, and the initial supply of water let into the settling-chamber direct from the water-supply pipe or supply-chamber, in which latter, however, the water is heated before entering the settling-chamber. By such arrangement the sediment is also free to deposit in the first instance in the settling-chamber without liability of clogging up small piping, as in cases where the water passes through a return-coil before entering the settling-chamber.

A further feature consists in an upper distributing-chamber connected with and supported by a set of water-pipes rising from the base portion of the apparatus, the said upper distributing-chamber being separate from the inclosing-drum, and arranged somewhat below or lower down than the top of the drum, in order that it may rise and fall with the expansion and contraction of the water-pipes. This feature avoids breakage of the parts as well as

involving other advantages, as will be herein-after seen.

A further feature consists in providing said upper distributing-chamber with discharge 5 and blow-off pipes extending through the top of the drum and susceptible of an end movement through said top, whereby they may move with any rise and fall of the drum.

A further feature consists in the herein-after 10 described annular settling-chamber constituting the base of the apparatus and having a uniform depth throughout its entire area, combined with and surrounding the straight steam-passage, which for the entire distance 15 between the horizontal planes of the top and bottom of said chamber extends vertically and centrally up through the chamber, whereby a comparatively large area of water-space of uniform depth throughout is formed around 20 the straight vertical steam-passage, and the said chamber freed from the presence of any obstruction whereon sediment may lodge, in place of settling directly upon the bottom of the chamber. Such construction, form, and 25 arrangement of settling-chamber will be readily distinguished from a heretofore-proposed construction of settling-chamber provided with a sloping bottom and combined with a steam-inlet pipe or passage having within the 30 chamber a horizontal portion entering adjacent to the shallower part thereof, thereby affording an obstruction whereon sediment may collect, in place of settling upon the bottom of a chamber of uniform depth, as in my im- 35 provement, wherein the premature collection in depth of sediment at any particular point in the chamber is avoided, and hence the danger of clogging up any inlet or circulating pipe or passage over or adjacent to such point obvi- 40 ated. In addition to this, the sediment which has collected in my improved form of chamber can be readily cleaned out by manual operation, since there is a clear space around the vertical steam-passage and between the hori- 45 zontal top and bottom of the chamber.

Further features consist in certain combinations and organizations tending to the general efficiency of the apparatus.

In the drawings, Figure 1 is a vertical central section of feed-water apparatus embodying the principles of my invention. Fig. 2 is 50 a transverse section of the same on the line *xx* of Fig. 1.

The steam-chamber A, which is formed with- 55 in a suitable shell or casing, A', is connected at its bottom with a steam-inlet, A², and at its side with the exhaust or discharge outlet A³, which latter is desirably located at a point adjacent to or not far above the bottom of the 60 said steam-chamber.

The system of return water-pipes, herein shown as contained within the steam-chamber, is as follows: An ordinary water-conducting pipe, *b*, which in practice is connected with a 65 suitable source of water-supply, enters the steam-chamber at the upper portion of the latter, and shortly after its entrance into said

chamber is expanded to provide or is connected with a pipe or chamber, B, which extends downwardly through the steam-chamber, 70 and which may be regarded as an enlarged water-supply pipe or a water-supply chamber inclosed within the steam-chamber. The water-supply pipe or chamber B is, by preference, arranged centrally within the steam- 75 chamber, in order that the water therefrom may be more conveniently distributed to one or more series of return water-pipes, which are in communication with the lower portion of the supply pipe or chamber B, and which stand 80 around the same. These said return water-pipes, which thus communicate at their lower ends with the supply pipe or chamber B, rise from the lower portion of the steam-chamber and are at their upper ends placed in communication with a discharge-pipe, C, which is common to all of said return-pipes, and which serves as a means for feeding the heated water to a boiler.

As a means for placing the water-supply 90 pipe or chamber B in communication with the return water-pipes, said supply pipe or chamber is at its lower end connected with an annular water-chamber, D, with which latter the upwardly-extending return-pipes are connected. This chamber D not only serves as an efficient means for supplying the said upwardly-extending return-pipes, but, being arranged at the base of the apparatus, it also provides a desirable settling-chamber having 95 a capacity which permits the accumulation of considerable sediment without rendering it necessary to frequently blow off the sediment which has accumulated therein. In order to promote the efficiency of chamber D for the 100 last-named purpose, it is provided with a suitable hand-hold plate, D', or the like, whereby access may be had to it when so desired.

By arranging the annular chamber D around the steam-inlet pipe or passage A² the water 110 within said chamber will be subject to the heated wall or pipe of said inlet, and at the same time the latter will be placed in position to enter the steam-chamber at or about the center of its bottom, so as to permit an effective 115 distribution of the steam about the water-pipes contained within the steam-chamber, as will be hereinafter more particularly referred to. In order to place the said return water-pipes in communication with the discharge- 120 pipe C, all of said pipes are desirably connected with an annular water-chamber, E, arranged within and at the upper portion of the steam-chamber A. By such arrangement the pipe *b* can be extended down through the 125 space *e*, which is bounded by said annular chamber.

The return-pipes, which are connected at their lower ends with the lower water-chamber D and at their upper ends connected with the 130 upper water-chamber D, are desirably arranged around the water-supply pipe or chamber B, so as to constitute two sets, the pipes F of the set nearest the water-supply pipe or cham-

ber being either arranged to form an annular series, as in Fig. 2, or irregularly distributed, as may be desired, while the set of pipes F', which are farthest from the water-supply pipe or chamber, are arranged to form an annular series, preferably concentric to the inner wall of the steam-chamber. The pipes F' of this said annular series are connected together by partition strips or webs f, which extend the length of the pipes, in which way an annular chamber, a, extending nearly the height of the steam-chamber, is formed between the inner wall of the steam-chamber and the web-connected pipes, which latter constitute, in effect, a cylindric partition, containing, however, a series of pipes which are exposed to the steam on both sides of said partition. The main steam-chamber A is by this arrangement divided for the greater portion 20 of its length into two communicating chambers, a and a', the latter being the larger of the two and being more directly connected with the source of steam-supply.

Steam entering through the inlet A² is first received within the larger subdivision a' of the steam-chamber, in which said subdivision the steam circulates upward and around the pipes exposed therein, and from thence it passes through the space or passage e, formed 30 by the annular chamber E, so as to reach the upper portion of the steam-chamber, from whence it passes downwardly through the annular chamber or annular subdivision a of the steam-chamber to the exhaust-outlet A³. During this return or downward passage of the steam it will be in contact with those portions of the outer annular series of return-pipe which, by reason of their web-connection, are exposed within said annular chamber a.

By the foregoing arrangement the steam is equally distributed over the surface of all of the water-pipes, and since it circulates first from one end of the heater to the other and then back to a point adjacent to the inlet end 45 of the steam-chamber the full value of the steam is utilized.

It will be observed that by the arrangement of return water-pipes I obtain a circulation of water from one end of the heater to the other 50 and then back to the end of the heater at which it first entered, thereby insuring its becoming properly heated. It will also be seen that the feed-water is not in contact with the outer shell of the heater, as in cases where the water-chamber is formed by said shell and steam-pipes submerged in the water; and hence by 55 my arrangement there is no liability of the feed-water becoming cool by contact with the said shell or casing. The large chamber or subdivision a' of the steam-chamber permits the expansion of the exhaust-steam which enters through inlet A, whereby there is an absolute freedom from back-pressure.

The circulating-chamber E, at the upper 60 end of the steam-chamber, while constituting an efficient circulating-chamber for the heated water from pipes F and F', also serves as a

scum-chamber, and in view of such capacity it is provided with a pipe, e', extending up through the top wall of the steam-chamber 70 and equipped with a blow-off cock, e².

It will be observed that the water-inlet pipe b, the blow-off pipe e', and the pipe C, which is to be connected with a boiler, and which will usually have a safety-valve, all extend up 75 through suitable stuffing-boxes at the top of the steam-chamber, in which way the pipes or tubes confined within the steam-chamber will not, by reason of longitudinal expansion or contraction, work loose at their point of connection with the top of chamber D, that forms a bottom for the subdivisions of the steam-chamber, it being obvious that the pipes can be fitted so as to be susceptible of a desirable 80 latitude of end movement through their respective stuffing-boxes.

The centrally-arranged water-supply pipe or water-supply chamber B can be connected in any suitable way with the lower and distributing settling-chamber D—as, for example, 90 by means of a pipe-connection, b', as shown in Fig. 1, wherein said pipe extends a short way down into the steam-inlet port or passage A².

What I claim as my invention is—

1. In a feed-water heater, the two concentrically-disposed steam-chambers, whereof the inner steam-chamber communicates with the surrounding outer steam-chamber solely at one end, and is provided at its opposite end with the inlet through which steam is let into 95 the apparatus, combined with water-conducting passages having their walls exposed within both of said chambers, the outer one of these two chambers being provided with an outlet arranged whereby steam admitted into 100 the one chamber shall be compelled to first traverse the heating-surface therein exposed, and then pass through and traverse the heating-surface exposed in the other chamber, substantially as set forth.

2. In a feed-water heater, the inner and outer communicating steam-chambers combined with a series of water-pipes incorporated in the partition-wall between the two steam-chambers and exposing portions of their surfaces in both of said chambers, whereby an enlarged area of heating-surface is exposed to steam within the two chambers, substantially 115 as set forth.

3. In a feed-water heater, the combination, with a steam-chamber, of the centrally-disposed water-supply pipe B, opening at one end into and supplying a lower settling-chamber, and a set of return water-pipes, F, leading up from the said settling-chamber and surrounding the 120 water-supply chamber, whereby a large area of heating-surface is exposed within the steam-chamber, the water conducted through the same by comparatively small passages, and an efficient provision made for the deposit of 130 sediment, substantially as described.

4. In a feed-water heater, the combination, with a steam-chamber, of the centrally-disposed water-supply chamber B, a lower set-

ting-chamber supplied from the centrally-disposed water-chamber and surrounding a steam-passage which opens into the steam-chamber, and return water-pipes leading upwardly from the settling-chamber and surrounding the centrally-disposed water-supply chamber, the said centrally-disposed water-chamber being in alignment with the steam-inlet, but contracted just above the point where the steam-inlet opens into the steam-chamber, whereby steam admitted into the steam-chamber shall be deflected by the water-supply chamber toward the surrounding water-pipes, substantially as described.

15 5. In a feed-water heater, a set of water-pipes rising from a settling-chamber at the base of the heater, combined with an upper distributing-chamber communicating with and supported within a steam-receiving drum or casing by the upper ends of said water-pipes, said upper distributing-chamber being disposed below and separate from the top of the chamber within the steam-receiving drum and being free to bodily rise or fall with the expansion or contraction of the water-pipes independently of the surrounding walls of the drum, substantially as and for the purpose described.

6. In a feed-water heater, a set of water-pipes rising from a source of water-supply at the base of the heater, combined with an upper distributing and scum chamber, E, sustained by and communicating with the water-pipes at their upper ends, said upper distributing and scum chamber being set below the top of the main inclosing-drum, substantially as set forth, and having discharge and blow-off pipes extending up through the top of the drum in a manner whereby upon the expansion or 40 contraction of the water-pipes the said upper distributing-chamber may rise and fall independently of the drum, and its discharge and blow-off pipes work longitudinally through the top of said drum, substantially as described.

45 7. In a feed-water heater, the two concen-

trically-disposed chambers *a* and *a'*, combined with a series of pipes, F, disposed within the inner chamber, a series of pipes, F', incorporated within the wall intervening between the two chambers, a steam-inlet passage leading into the inner chamber, at the bottom thereof, and a passage connecting the said inner chamber at its upper end with the outer steam-chamber, which latter is provided at a lower point with an outlet, substantially as described.

8. In a feed-water heater, the combination, with the two concentrically-disposed steam-chambers, of a set of water-pipes rising from a settling-chamber at the base of the apparatus and extending up through the inner one of the two concentrically-disposed steam-chambers, an upper annular distributing-chamber, F, communicating with and supported by the said water-pipes, said annular distributing-chamber serving to close the upper end of the inner steam-chamber, except at the point where it provides a passage, *c*, which said passage opens into an upper steam-space above the annular chamber E, and communicating with the outer annular steam-chamber, *a'*, substantially as described.

9. In a feed-water heater, the herein-described annular settling-chamber D, constituting the base of the apparatus and having a uniform depth throughout its entire area, combined with and surrounding the straight steam-passage A², which for the entire distance between the horizontal planes of the top and bottom of said chamber extends vertically and centrally up through the chamber, whereby a comparatively large area of water-space of uniform depth throughout is formed around the straight vertical steam-passage, and the said chamber freed from the presence of any obstruction whereon sediment may lodge, in place of settling directly upon the bottom of the chamber, substantially as shown and set forth.

ALFRED M. ROWE.
